UNITED STATES PATENT OFFICE.

MARY G. HATCH, OF NEW YORK, ASSIGNOR TO M. H. BIRGE & SONS, OF BUFFALO, NEW YORK.

DESIGN FOR WALL-PAPER.

SPECIFICATION forming part of Design No. 23,667, dated October 2, 1894.

Application filed September 4, 1894. Serial No. 522,137. Term of patent 3½ years.

To all whom it may concern:

Be it known that I, MARY G. HATCH, a citizen of the United States, residing at New York, in the county and State of New York, have 5 invented and produced a new and original Design for Wall-Paper, of which the following is a specification.

The design consists of a series of groups of parallel lines forming vertical stripes on 10 which are placed running vines of the sweet pea with flowers and leaves, and separated by narrow vertical stripes formed of parallel lines as represented in the accompanying drawing.

15 The border or upper portion of the design is formed of a series of interlaced vines of

the sweet pea with flowers and leaves interlacing, with a series of interlaced segments of circles formed of light lines and top ornaments as shown in the drawing. The border 20 is separated from the hanging by a horizontal band formed of parallel lines as shown.

What I claim is—

The design for wall paper herein shown and described. 25

Witness my hand this 24th day of August, 1994.

MARY G. HATCH.
